(57) **CLAIM**

The ornamental design for a dashboard device as shown and described.

DESCRIPTION

FIG. 1 is a front view of a dashboard device;

FIG. 2 is a top view thereof;

FIG. 3 is a bottom view thereof;

FIG. 4 is a left side view thereof;

FIG. 5 is a right side view thereof;

FIG. 6 is a back view thereof;

FIG. 7 is a front, top right perspective view thereof;

FIG. 8 is a back, top right perspective view thereof; and,

FIG. 9 is a cross-sectional view thereof, taken line 9-9 of FIG. 1.

The broken line in FIG. 1 illustrates the cross-sectional cut plane of the dashboard device that forms no part of the claimed design.
